(57) **CLAIM**

I claim the ornamental design for the gutter cover, as shown and described.

DESCRIPTION

FIG. 1 is a top perspective view of a gutter cover according to a first embodiment;

FIG. 2 is another top perspective view of FIG. 1;

FIG. 3 is a left side view of FIG. 1;

FIG. 4 is a right side view of FIG. 1;

FIG. 5 is an end view of FIG. 1;

FIG. 6 is an end view opposite to the end view of FIG. 5;

FIG. 7 is a top view of FIG. 1;

FIG. 8 is a bottom view of FIG. 1;

FIG. 9 is a top perspective view of a gutter cover according to a second embodiment;

FIG. 10 is another top perspective view of FIG. 9;

FIG. 11 is a left side view of FIG. 9;

FIG. 12 is a right side view of FIG. 9;

FIG. 13 is end view of FIG. 9;

FIG. 14 is an end view opposite of FIG. 13;

FIG. 15 is a top view of FIG. 9; and,

FIG. 16 is a bottom view of FIG. 9.

The gutter cover is shown with a symbolic break in its length. The appearance of any portion of the gutter cover between the break lines forms no part of the claimed design.
